UNITED STATES PATENT OFFICE.

REGINALD A. FESSENDEN, OF BROOKLINE, MASSACHUSETTS, ASSIGNOR TO SUBMARINE SIGNAL COMPANY, OF PORTLAND, MAINE, A CORPORATION OF MAINE.

APPARATUS FOR DIRECTIVE SIGNALING.

1,355,598.

Specification of Letters Patent. Patented Oct. 12, 1920.

Application filed August 16, 1917. Serial No. 136,827.

To all whom it may concern:

Be it known that I, REGINALD A. FESSENDEN, of Brookline, in the county of Norfolk and State of Massachusetts, a citizen of the 5 United States, have invented a new and useful Improvement in Apparatus for Directive Signaling, of which the following is a specification.

My invention relates to the transmission 10 and receipt of energy and more particularly to signaling and still more particularly to directional signaling, especially the location of submarines and submarine signaling stations and also of aeroplanes.

15 The object of my invention is to improve the efficiency of the sending and receiving energy and more especially to improve the efficiency of signaling and still more to improve the efficiency of apparatus and methods 20 for locating submarine signaling stations and submarines. It may be used on shipboard or otherwise.

The figure accompanying this specification illustrates, partly diagrammatically, apparatus adapted for carrying out my invention.

In the figure, 33 is a vessel for example 30 of the destroyer type and 30, 31 and 32 are the compartments of the forepeak or oil tanks of the torpedo destroyer, though they 35 may be fluid containers otherwise located, according to circumstances.

11 and 12 are sound receiving devices of any suitable kind; for example, microphones or stethoscopes, or electro-magnetic receivers and preferably oscillators of the kind described in United States Patent No. 1,167,366. I shall hereinafter refer to these, generally speaking, as sound detectors.

40 These oscillators are shown as located on board ship and are placed in any suitable position with reference to each other, either side by side, or, as shown, back to back in the same tank or adjacent fluid containing 45 tanks, and preferably have their faces perpendicular to the skin of the ship. As shown, they are separated by the sound insulating screen 13, 14, of any kind, being attached to each other and to it by the bolts 50 15, 16, which may be insulated therefrom by soft rubber or lead in a known way.

Both oscillators and sound screen are mounted on a pivot 29 and can be rotated by any suitable means, as for example, by 55 the handle 17.

The sound screen 13, 14, may be constructed and shaped in any suitable way to produce the desired result; for example, at the end 14 the sound screen is shown in curved shape so as to shield to a greater extent than at the end 13. 60

I prefer so to shape the sound screen 13, 14 that a sound coming from a given angle and striking the oscillators will be heard with the same relative intensities and phases 65 as a sound coming from the same angle and striking the head of a human being.

The shape of the sound screen to accomplish this is best determined by experiment, the shape being varied until a person listening in on telephone receivers attached to the oscillators will obtain the same change in 70 relative sound intensities in the two receivers when the oscillators are turned to a certain angle as he obtains when he turns his 75 head through the same angle.

An important point to note is that when the oscillators are used in a different medium from air, for example in water, the distance of the oscillators apart should 80 preferably bear the same relation to the velocity of sound in such medium, for example water, as the usual distance apart of the two ears of a human body bears to the 85 velocity of sound in air. For example, if the distance between the ears is 8 inches and the velocity of sound in air is 1100 feet per second, then if the oscillators are immersed in water, in which the velocity of 90 sound is 4400 feet per second, the oscillators should preferably be placed a little less than 3 feet apart. If the oscillators are placed farther apart, as for example, 10 feet, still further changes are obtained and the sound screen must be extended still farther in 95 order to obtain the desired effect on turning the oscillators around on their pivot 29.

18, 19, 20, 21 are leads from the oscillators to the indicators shown as telephone receivers 26, 27, which with the other apparatus 100 may be located upon the bridge or other convenient place and are connected by the head band 28 but are not electrically connected to each other.

33 and 34 are switches for opening or closing the lead circuits as desired. 105

22, 23 are adjustable capacities, and 24, 25 are adjustable inductances. These capacities and inductances have the function, in addition to their other functions, that by 110

changing their relative values the phase of the sounds reaching the receivers 26, 27, can be altered without turning the oscillators on their pivot, or, if the oscillators are turned 5 on their pivot, the change of phase may be increased or decreased.

For example, if a sound is received on the port bow, the oscillators may be either turned by means of the handle 17 until the 10 sound appears to come from a point perpendicular to and in front of the line joining the centers of the diaphragms of the two oscillators, the sound then being equally 15 loud to both ears of the observer, and the angle through which the handle 17 is being moved may be measured and the exact direction of the sound be thus determined. Or the oscillators may be left stationary and the condensers 22, 23, or inductances 24, 25, 20 or both, adjusted until the sound appears dead ahead and the readings of the condensers and inductances taken and in this way the exact direction determined. Or both oscillators and condensers and inductances 25 may be left stationary and the vessel turned until the sound appears to come in dead ahead and the bow is pointed in the direction of the source of sound.

The tanks 30, 31, 32 are preferably filled 30 either with water or oil, and when the oil is used up, it is preferably replaced with water.

The insertion of the oscillators in fluid 35 filled tanks, for example, forepeak tanks, or, as shown, in oil tanks, has the great advantage that, as applicant has discovered, it enables the sound to be received nearly as well dead ahead as abeam.

For example, with the installation placed 40 on the S. S. *Devereaux* the distance at which it was possible to send and receive dead ahead was 31½ miles as against 36 miles abeam. With the installation placed on the U. S. destroyer *Aylwin* the working dis- 45 tance dead ahead was 84% of that abeam.

I have discovered that it is possible to still further increase the range dead ahead or dead astern by making the skin of the ship or the wall of the tanks or the chamber 50 containing the sound receiver so that the index of sound refraction of the skin of the ship or the wall of the tanks relative to water is unity.

For example, the velocity of sound in 55 water is approximately 4400 feet per second, while the velocity of sound in steel is approximately 17,000 feet per second. Consequently, sounds striking the skin of the ship at a small angle are totally reflected and do 60 not enter the ship and affect the oscillators.

I have found, however, that by loading 65 the skin of the ship so that the index of refraction of the skin of the ship or the wall of the tanks relative to water is unity, not only are water noises greatly lessened

but also sound passes directly from the signaling station to the oscillator, almost as if the skin of the ship were not there.

One method by which I accomplish this is to electrically weld, or otherwise suitably attach, lumps or disks or plates of lead or other suitable material, such as tungsten, to the inside of the skin of the ship, or to use material such as zinc or tin or tin alloyed with lead, or to use a plate having holes punched in it, the holes being filled with lead or brass. Other arrangements may suggest themselves, but whatever the arrangement used, it should be such as to make the index of refraction of the skin of the ship or the wall of the tanks relative to water equal to unity, and if weights are used, such as disks of lead, they should be close together, *i. e.*, the distance between any two adjacent ones should be approximately equal to less than a quarter wave length of the sound which is to be received.

This method is also of value as a method of eliminating high pitched sounds which it is not desired to receive, as sounds whose quarter wave length is less than the distance between the weights may be refracted while sounds of longer wave length will be transmitted.

Other arrangements of apparatus to accomplish this result and be within the scope of my invention will occur to those skilled in the art.

What I claim is:

1. The combination of a fluid container, 100 two sound detectors located in the fluid in said fluid container, a sound screen located between said sound detectors, and two indicators, each connected to one of the sound detectors, said sound screen being shaped 105 as described whereby it will produce a sound shadow with relation to said detectors similar to that produced by the human head with relation to the ears.

2. The combination of a fluid container, 110 two sound detectors located in the fluid in said fluid container, a sound screen located between said sound detectors, and two indicators, each connected to one of the sound detectors, said sound screen being proportioned 115 with relation to said detectors approximately as the human head is to the location of the ears.

3. The combination of a fluid container, 120 two sound detectors located in the fluid in said fluid container, and two indicators, each connected to one of the sound detectors, the connections between said detectors and indicators comprising inductances and capacities adapted to vary the current phase generated by the detectors and received by the indicators.

4. A tank and a sound detector located 125 therein, a wall of said tank having its index for refraction of sound relative to water

- substantially the same as that of the medium outside the tank through which the signals are sent and received.
5. A tank and a sound detector located therein, a wall of said tank being loaded with weights separated from each other by a distance approximately less than one quarter wave length of the desired sound wave in the medium through which the desired signals are transmitted and received whereby the index of refraction of said wall will be made substantially the same as water.
10. A tank and a sound detector located therein, a wall of said tank being loaded with weights separated from each other by a distance approximately less than one quarter wave length of the desired sound wave in the medium through which the desired signals are transmitted and received whereby the index of refraction will be increased.
15. A tank and a sound signaling device located therein, a wall of said tank being loaded with weights separated from each other by a distance approximately less than one quarter wave length of the desired sound wave in the medium through which the desired signals are transmitted and received whereby the index of refraction of said wall will be made substantially the same as water.
20. A tank and a sound signaling device located therein, a wall of said tank being loaded with weights separated from each other by a distance approximately less than one quarter wave length of the desired sound wave in the medium through which the desired signals are transmitted and received whereby the index of refraction will be increased.
25. A tank and a sound signaling device located therein, a wall of said tank being loaded with weights separated from each other by a distance approximately less than one quarter wave length of the desired sound wave in the medium through which the desired signals are transmitted and received whereby the index of refraction of said wall will be made substantially the same as water.
30. A tank and a sound signaling device located therein, a wall of said tank being loaded with weights separated from each other by a distance approximately less than one quarter wave length of the desired sound wave in the medium through which the desired signals are transmitted and received whereby the index of refraction will be increased.
35. The combination of two electric circuits, two electrically-operating sound detectors connected to said electric circuits and adapted to cause currents of varying intensity to flow in said electric circuits upon the receipt of sound waves, indicating means connected to said electric circuits adapted to produce an indication on the receipt of sounds, and means, comprising inductances and capacities located in said electric circuits, adapted to vary the phase of the varying currents caused to flow by the received sounds in each of said circuits relatively to the other.
40. The combination of two electric circuits, two electrically-operating sound detectors connected to said electric circuits and adapted to cause currents of varying intensity to flow in said electric circuits upon the receipt of sound waves, indicating means connected to said electric circuits adapted to produce an indication on the receipt of sounds, and means, comprising inductances and capacities located in said electric circuits, adapted to vary the phase of the varying currents caused to flow by the received sounds in each of said circuits relatively to the other.
45. The combination of two electric circuits, two electrically-operating sound detectors connected to said electric circuits and adapted to cause currents of varying intensity to flow in said electric circuits upon the receipt of sound waves, indicating means connected to said electric circuits adapted to produce an indication on the receipt of sounds, and means, comprising inductances and capacities located in said electric circuits, adapted to vary the phase of the varying currents caused to flow by the received sounds in each of said circuits relatively to the other.
50. The combination of two electric circuits, two electrically-operating sound detectors connected to said electric circuits and adapted to cause currents of varying intensity to flow in said electric circuits upon the receipt of sound waves, indicating means connected to said electric circuits adapted to produce an indication on the receipt of sounds, and means, comprising inductances and capacities located in said electric circuits, adapted to vary the phase of the varying currents caused to flow by the received sounds in each of said circuits relatively to the other.
55. The combination of two electric circuits, two electrically-operating sound detectors connected to said electric circuits and adapted to cause currents of varying intensity to flow in said electric circuits upon the receipt of sound waves, indicating means connected to said electric circuits adapted to produce an indication on the receipt of sounds, and means located in said electric circuits, adapted to vary the phase of the varying currents caused to flow by the received sounds in each of said circuits relatively to the other.
60. The combination of two electric circuits, two electrically-operating sound detectors connected to said electric circuits and adapted to cause currents of varying intensity to flow in said electric circuits upon the receipt of sound waves, indicating means connected to said electric circuits adapted to produce an indication on the receipt of sounds, and means located in said electric circuits, adapted to vary the phase of the varying currents caused to flow by the received sounds in each of said circuits relatively to the other.
65. The combination of two electric circuits, two electrically-operating sound detectors connected to said electric circuits and adapted to cause currents of varying intensity to flow in said electric circuits upon the receipt of sound waves, indicating means connected to said electric circuits adapted to produce an indication on the receipt of sounds, and means located in said electric circuits, adapted to vary the phase of the varying currents caused to flow by the received sounds in each of said circuits relatively to the other.
70. The combination of two electric circuits, two electrically-operating sound detectors connected to said electric circuits and adapted to cause currents of varying intensity to flow in said electric circuits upon the receipt of sound waves, indicating means connected to said electric circuits adapted to produce an indication on the receipt of sounds, and means, comprising inductances and capacities located in said electric circuits, adapted to vary the phase of the varying currents caused to flow by the received sounds in each of said circuits relatively to the other, and adapted to determine the direction from which the sounds are received.
75. A submarine signaling apparatus comprising a liquid container, two submarine signaling mechanisms located in the liquid in said container, and means for varying the angle between the line joining the center of said two submarine signaling mechanisms and a second line drawn through the center of said first line and terminating at opposite sides of said container.
80. A submarine signaling apparatus comprising a container, a submarine signaling mechanism located within said container, one wall of said container being adjacent to the medium through which the signals are sent and received, said wall of said container having its index of refraction of sound relative to water substantially the same as that of the medium outside the container whereby signals are transmitted and received in directions substantially parallel to the plane of said wall of said container with increased efficiency and loudness.
85. A submarine signaling apparatus comprising a container, a submarine signaling mechanism located within said container, one wall of said container being adjacent to the medium through which the signals are sent and received, said wall of said container having its index of refraction of sound relative to water substantially the same as that of the medium outside the container whereby signals are transmitted and received in directions substantially parallel to the plane of said wall of said container with increased efficiency and loudness.
90. A liquid container, a submarine signaling mechanism located therein, a wall of said container having weights attached thereto, the distance between said weights being less than the quarter wave length of the signals in the liquid, whereby the index of refraction of sound relative to water of said wall may be made to have a desired value.
95. A container, a submarine signaling mechanism located therein, a wall of said container having localized inertia whereby its index of refraction of sound relative to water may be made to have any desired value.
100. A container, a submarine signaling mechanism located therein, a wall of said container having localized inertia whereby its index of refraction of sound relative to water is made substantially the same as that of the medium outside the container through which the sounds are sent and received.
105. A container, a submarine signaling mechanism located therein, a wall of said container having localized inertia whereby its index of refraction of sound relative to water is made substantially the same as that of the medium outside the container through which the sounds are sent and received.
110. A container, a submarine signaling mechanism located therein, a wall of said container having localized inertia whereby its index of refraction of sound relative to water is made substantially the same as that of the medium outside the container through which the sounds are sent and received.
115. A container, a submarine signaling mechanism located therein, a wall of said container having localized inertia whereby its index of refraction of sound relative to water is made substantially the same as that of the medium outside the container through which the sounds are sent and received.
120. A container, a submarine signaling mechanism located therein, a wall of said container having localized inertia whereby its index of refraction of sound relative to water is made substantially the same as that of the medium outside the container through which the sounds are sent and received.
125. A container, a submarine signaling mechanism located therein, a wall of said container having localized inertia whereby its index of refraction of sound relative to water is made substantially the same as that of the medium outside the container through which the sounds are sent and received.

REGINALD A. FESSENDEN,
